(57) **CLAIM**

The ornamental design for a nose hair trimmer, as shown and described.

DESCRIPTION

FIG. 1 is a top perspective view of the present nose hair trimmer;

FIG. 2 is a left side view of the nose hair trimmer of FIG. 1;

FIG. 3 is a right side view of the present nose hair trimmer;

FIG. 4 is a front view of the present nose hair trimmer;

FIG. 5 is a rear view of the nose hair trimmer of FIG. 1;

FIG. 6 is a top view of the nose hair trimmer of FIG. 1; and,

FIG. 7 is a bottom view of the nose hair trimmer of FIG. 1. The broken lines illustrate portions of the nose hair trimmer that form no part of the claimed design.
